UNITED STATES PATENT OFFICE

EDWARD AUGUSTUS SHIVER, OF CINCINNATI, OHIO, ASSIGNOR, BY MESNE ASSIGNMENTS, TO CINCINNATI GRINDERS INCORPORATED, OF CINCINNATI, OHIO, A CORPORATION OF OHIO

WHEEL DRESSER

Application filed January 3, 1924. Serial No. 684,126.

This invention relates to means for dressing the grinding wheels of grinding machines, and is of particular utility when embodied in the construction of grinding machines of the type in which the articles to be treated are supported on centres carried by an adjustable head-stock and an adjustable tail-stock, respectively, and are presented rotatively for the grinding action of a wheel between which and the workpiece there is a relative movement along their axes of rotation.

An important objective of the invention is to provide a wheel-dresser which is organized as a permanent instrumentality of the grinding apparatus, and can be quickly and easily set in position for dressing the grinding wheel, and can be as readily stowed out of the way, without the laborious detail of bodily detaching and removing the device entirely from the grinding-machine; an operation which must be performed with conventional dressers, the construction of which does not permit stowing away the dressing device and its support in situ.

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:—

In the drawings, Fig. 1 is a perspective of a grinding apparatus shown with a wheel-dresser embodying the invention; only so much of the apparatus being shown as is essential to illustrate the improvements. Fig. 2 is a transverse vertical section of the work-supporting bed, with the wheel-dresser shown in elevation, and a fragment of the wheel being dressed. Fig. 3 is a rear elevation of the wheel-dresser, isolated, with a fragment of the bed. Fig. 4 is a perspective

of the apparatus shown in Fig. 1, but with the wheel-dresser stowed in situ, clearing the working space for a workpiece, which is shown in place. Fig. 5 is a vertical sectional view, of a diagrammatic character, similar to Fig. 2, but on a larger scale, showing contiguous parts of the grinding wheel and workpiece, and illustrating by dotted lines the comparative position of the wheel-dresser when substituted for the workpiece.

In the illustrated embodiment of the invention, parts of a conventional grinding apparatus are shown, including a grinding wheel 1, and a work-supporting bed 2, with a head-stock 3 and a tail-stock 4 having respectively the usual centers 5 and 6 to hold a workpiece in position for treatment by the wheel 1, such a workpiece being shown at 7 in Figs. 4 and 5, while the reference character 8 designates the usual slideways, and 9 designates the attachment groove usually found in the face of such bed, for adjustable attachment of the stocks 3 and 4.

In accordance with the invention, a wheel-dresser is provided, as an organized instrumentality of the grinding apparatus, occupying a permanent position adjacent to the grinding wheel 1, and of such construction that it can be set up for action, as shown in Figs. 1, 2, and 3, where it occupies the position ordinarily devoted to the workpiece, or it can be stowed in situ, out of action, when not required for dressing operations.

This stowability of the wheel-dresser, in assembled relation with the grinding apparatus, differentiates the present improvements from conventional structure, and any suitable means may be adopted to effect the purpose. As one convenient structure, the wheel-dresser is shown as comprising an attachment-member or base 11, and a tool-holder 12, hinged to the base by pintles or pivots 13; the tool-mount 10, tool 14 and setscrew 15 being shown as of conventional structure, which can however be varied as required.

The base 11 preferably has means 16, such as the inverted T-shaped bolt which is illustrated, to secure the wheel dresser firmly in

adjusted position, as a unitary structure, and its basic position need rarely be changed.

Its stability in adjusted position may be promoted by the provision of feathers 17 taking into the ways 8, as shown in Fig. 2, and preventing the wheel-dresser from slew-ing around on the bolt 16. When inopera-tive, the tool-holder 12, with the tool 14 still in place if desired, will rest upon the bed 2 in the position shown in Fig. 4.

In operation, the tool-holder 12 is swung upward from its position of Fig. 4, through the dotted line position of Fig. 3, to the op-erative position shown in full lines in Figs. 1, 2 and 3, and indicated in dotted lines in Fig. 5. In order to maintain the tool-holder firmly in this operative position, with the tool 14 presented in dressing relation with the grinding wheel 1, an abutment 18 is prefer-ably provided, integral with the base 11, and at a suitable height above the base 11 this abutment is engaged by a lug 19 on the tool-holder, and a link 20, with thumb-nut 21, may be provided, to swing around an axis 22, and enter the notch 23 of a fork at the upper end of abutment 18, the nut 21 being then tight-ened to draw the lug 19 against the abutment shoulder 23, as shown in Fig. 3.

The grinding wheel 1 is then rotated and dressed as usual, by the tool 14, and Fig. 5 illustrates the accuracy with which the tool may be brought into position to dress the wheel 1 at its working region, this position corresponding closely with that to be occu-pied in due time by a workpiece 7, which is shown in full lines in Fig. 5. The wheel-dresser is shown in dotted lines, by way of comparison.

When the dressing is finished, the tool-holder 12 is released by unscrewing the wing-nut 21, swinging the link 20 up, and swinging the tool-holder 12 down, preferably with the tool 14 in place, so that they lie flat in situ on the bed 2, not interfering in the least with the emplacement and grinding of as many pieces of work 7 as can be treated before it becomes necessary to dress the grinding wheel 1 again when the above operation may be repeated.

Accordingly, the wheel-dresser thus or-organized as part of a grinder, and taking the form of an adjustable and stowable per-manent attachment, constitutes a notable source of economy in time and labor, and renders the dressing of a grinding wheel such a simple operation that the workman is in-duced thereby to keep the grinding wheel in better dress than when, in each conventional dressing operation, he had to install the com-plete tool-stock and tool, and then remove the same.

Without further analysis, the foregoing will so fully reveal the gist of this invention that others can, by applying current knowl-edge, readily adapt it for various utilizations by retaining one or more of the features that,

from the standpoint of the prior art, fairly constitute essential characteristics of either the generic or specific aspects of this inven-tion and, therefor, such adaptations should be, and are intended to be, comprehended within the meaning and range of equivalency of the following claims:

Having thus revealed this invention, I claim as new and desire to secure the follow-ing combinations and elements, or equiva-lents thereof, by Letters Patent of the United States:—

1. Grinding apparatus, comprising a work-supporting bed, a grinding wheel, a wheel-dresser organized therewith and comprising a base-member adjustably secured upon said bed, a tool-holder hinged to said base mem-ber below a horizontal plane intersecting the axis of the grinding wheel and adapted to be swung upwardly into vertical alignment with the axis of the hinge into wheel-dressing po-sition, an abutment provided by said base-member and adapted to limit the movement of said tool holder into wheel-dressing po-sition, and a positive locking-device comprising a locking element carried by said tool holder and adapted to engage said abutment positively to maintain said tool-holder in its wheel-dressing position.

2. Grinding apparatus, comprising a work-support, a grinding wheel, a wheel-dresser organized therewith, and comprising a base member secured upon said work-support, a tool-holder pivoted to said base member beneath the work and transverse to the axis thereof, an abutment provided by said base member and provided with a forked end, and a locking element carried by said tool-holder and adapted to releasably en-gage said forked end to maintain the tool-holder in its operative position.

3. Grinding apparatus, comprising a work-supporting bed; work-supporting head and tail stocks fixed to said bed; a grinding wheel, and a wheel-dresser organized therewith and movable in situ to occupy its wheel-dressing position, and alternatively to oc-serve a position of rest beneath the work-piece and flat upon said bed; said wheel-dresser having a base member fixed to said bed between said head and tail stocks and a tool-holding member pivoted to said base member adjacent said bed on an axis ar-ranged transverse to the axis of the grinding wheel; and means positively to maintain said tool holding member in wheel dressing po-sition with the dressing-tool in vertical alignment with the pivot between the base-member and the tool-holding member.

4. Grinding apparatus, comprising a work-support, a grinding wheel, and a wheel-dresser organized therewith having a base with means for securing said base adjustably to said work-support; a tool-holder hinged to said base and movable in situ to occupy a

vertical wheel-dressing position, and alternatively to occupy a horizontal position of rest, closely adjacent to said work-support, beneath the work-piece; a vertically disposed abutment provided by said base and adapted to limit the upward movement of said tool-holder to a vertical position; and positive locking means to maintain said tool-holder in wheel dressing position.

In witness whereof, I hereunto subscribe
my name.

EDWARD AUGUSTUS SHRIVER.
